REMOTE CONTROL UNIT FOR DISPENSING APPARATUS

Fritz Gallati, Zurich, Switzerland, assignor to Mettler Instrumente AG, Zurich, Switzerland

Filed July 31, 1970, Ser. No. 24,244

Term of patent 14 years

Int. Cl. D13—03

U.S. Cl. D26—13

Fig. 1

Fig. 2

Fig. 4

Fig. 3

FIG. 1 is a top plan view of the remote control unit for dispensing apparatus;

FIG. 2 is a side elevation view of the unit; and

FIGS. 3 and 4 are left and right hand end views, respectively of the unit.

The bottom surface of the remote control unit is planar and continuous.

I claim:

The new, original, and ornamental design for a remote control unit for dispensing apparatus, as shown and described.
